Harry V. Tuttle, S. Star Rte., Brush, Colo.

Filed May 29, 1961, Ser. No. 65,386

Term of patent 14 years

(Cl. D34—5)

FIG. 1 is a perspective view of a base ball practise device showing my new design;

FIG. 2 is a horizontal cross-section looking upwardly on the line 2—2, FIG. 1; and

FIG. 3 is a similar cross-section looking downwardly on the line 2—2, FIG. 1.

The dominant features of our design reside in the portion shown in full lines.

We claim:

The ornamental design for a base ball practice device, as shown and described.
